United States Patent Office.

THOMAS S. BOWMAN, OF ST. LOUIS, MISSOURI

Letters Patent No. 68,162, dated August 27, 1867.

IMPROVED MODE OF CLOSING BOTTLES.

The Schedule referred to in these Letters Patent and making part of the same.

TO ALL WHOM IT MAY CONCERN:

Be it known that I, THOMAS S. BOWMAN, of St. Louis, in the county of St. Louis, in the State of Missouri, have invented a new and useful Improvement in Bottles; and I do hereby declare that the following is a full, clear, and exact description thereof, which will enable others skilled in the art to make and use the same, reference being had to the accompanying drawings, and to the letters of reference marked thereon.

This invention consists in so constructing the neck of a bottle, and also a stopple for the same, in such a manner that when the bottle is once filled and stoppled, it cannot be opened without breaking some part of it, the object being to furnish a bottle for patent and proprietary medicines and mixtures that cannot be refilled and stoppled the same as the original bottle; but in order to prevent the spilling of the contents when it is desired to open the bottle, it is made so as to break at a certain designated point, as will be hereinafter described.

Figure 1 represents the bottle as corked and stoppled.

Figure 2 shows the bottle when broken.

Figure 3 is the stopple.

Figure 4 is a sectional view of the neck of the bottle, showing the position of the cork, stopple, and plaster of Paris; the cork in red, the stopple in blue, and the plaster of Paris in dots.

Similar letters of reference indicate like parts.

A is the bottle, B is the stopple, C is the cork, D is the plaster of Paris.

When the bottle is filled, the cork C is driven in in the position shown in figs. 1, 2, and 4. A small quantity of plaster of Paris, mixed with water to the proper consistency, is poured in on the cork C, and the stopple B is pressed in place. The plaster of Paris D sets in the groove in the neck of the bottle and the groove in the stopple, and holds the latter firmly in its position. The stopple is made large enough at its upper end to completely cover the mouth of the bottle, and prevent the removal of the plaster of Paris. In order that the bottle may be broken without spilling the contents, a sharp corner is formed in the same, at the point f' f, fig. 4, on the outside, and rounding at the same point on the inside, which tends to weaken the bottle at that place. By striking upwards at this weak part, that portion of the neck of the bottle containing the stopple B and the plaster of Paris D will break off, as shown in fig. 2, when the cork may be drawn the same as in an ordinary bottle.

What I claim as my invention, and desire to secure by Letters Patent, is—

1. The method of stoppling bottles, substantially as described.
2. The special construction and combination of the bottle-neck and stopple B, substantially as and for the purposes specified.

THOMAS S. BOWMAN.
